STOCKING

John M. Botts, Jenkintown, Pa.

Application November 28, 1934, Serial No. 755,116

2 Claims. (Cl. 66—183)

This invention relates to stockings and in particular to stockings that are self-sustaining upon the leg of the wearer.

Stockings of the customary construction require garters, such as those of the elastic band type or of the clasp type, for their support, and this results in inconvenience to the wearer and may also result, particularly in the case of clasp type garters, in damage to the stocking.

It is the general object of my invention to modify the construction of stockings in such a manner that they are self-sustaining and so that garters or other supporting accessories are unnecessary, thereby avoiding the inconvenience and damage due to such accessories used for the support of stockings. For this purpose I provide on a stocking, and formed as an integral part thereof, sections adapted to fulfill all the supporting functions of garters or other supporting devices.

For the attainment of the above-mentioned object and such other objects as will hereinafter appear or be pointed out, I have illustrated one embodiment of my invention in the drawing, in

which:

Figure 1 is a view of a stocking constructed in accordance with my invention, shown applied to the leg of a wearer; and

Figure 2 is a view showing the fabric of my stocking as it would appear after leaving the full fashioned machine used for its manufacture, and before seaming of the same to produce a finished stocking.

My invention has been illustrated by way of example in connection with a three quarter length stocking, in which the welt is a single layer fabric of the type set forth, in my Patent 1,833,705. However it will be understood that my invention is of broader application than to such specific example, which is illustrative merely, and that the disclosure herein is not to be interpreted in a limiting sense.

By referring to Figure 1 it will be observed that the stocking there shown comprises a welt portion 11 encircling the leg of a wearer at the narrowest portion thereof below the knee but above the swell of the calf, this stocking being of the type ordinarily designated as a "three-quarter length stocking" and that it further comprises the customary leg and foot portions, 13 and 15 respectively.

Referring now to Figure 2 for the details of my invention it will be observed that the welt portion 11 shown therein comprises a section of uniform transverse width, and having a plain

knit band 17, and a lace-work band 19, and a reinforcement 20 below the lace-work. This welt portion is made of such transverse width that in the finished stocking it will have a circumferential extent that will adapt it to grip that portion of the leg of the wearer to which it is applied, and at the same time it is made elastic enough to exert a resilient gripping action and so as to pass over the widest portion of the leg when the stocking is drawn thereover. The circumferential extent of the welt portion will naturally be determined by the circumference of the wearer's leg, and due to the great variation of this dimension it is found convenient, as customary, to group the stockings into various sizes, each one suitable for a definite range of leg circumferences. To give concrete figures, by way of example, 240 needles corresponding roughly to a circumference of 12½ inches are actually used in knitting the welt portion of one size of these stockings.

The height or longitudinal extent of the welt section will also vary with the dimensions of the wearer's leg. Generally a height of the order of two inches would be adequate.

While the welt portion 11 is shown as comprising the plain knit section 17 and the lace-work section 19, it will be obvious that it may be made otherwise. For instance it may be plain knit throughout.

To secure the necessary gripping action without interfering with the stretch necessary in order that the welt may pass over the calf portion, the yarn must be sufficiently strong and the character of knitting such that it will give the necessary yield and elasticity. For this purpose, to give an actual example by way of illustration, portion 17 may consist of 8 thread yarn while the lace work 19 may consist of 14 thread yarn.

The leg portion 13 is shown as having a central section 21 of such characteristics that it will fit comfortably around the swell of the calf of the wearer, and for this purpose it may be considerably wider than the welt portion just described. For example, where the welt portion is knitted with 240 needles, corresponding to a circumference of about 12½ inches, 304 needles corresponding to a circumference of about 15 inches, may be used for the section 21. While an increased diameter is disclosed herein it will be understood that the desired characteristics may also be attained otherwise, as will be pointed out hereinafter.

Intermediate the wide calf section 21 and the welt 11 is a section 23, which serves to unite the

section 21 to the welt, besides performing other functions to be described in what follows.

Where, as illustrated herein, the welt portion 11 and the calf portion 21 are of different widths, the intermediate portion 23 is preferably of a width increasing from the welt toward said calf portion, and this width is shown as increasing gradually and substantially uniformly, so that in its finished form, this section will conform to the contours of the leg, and the taper of the sides to obtain the increase in width is shown as symmetrical. It must however be pointed out that this is not necessarily so, as the width need not progress gradually nor uniformly, nor need 15 the contour of section 23 be symmetrical.

It will be obvious that where portions of the section 23 are made of a width less than that of section 21 and properly contoured, they will assist the welt 11 in its sustaining function, and 20 this function is present to a high degree in the construction as disclosed.

It will further be observed that in Figure 2, below the portion 21 is shown a tapered portion 25 merging into the foot portion 15, such, however, being the customary construction for full-fashioned stockings, and not a part of my invention. These portions are here referred to mainly to make clear the process of knitting the portion 23.

30 As is well known the tapered effect of section 25 is obtained by that process of knitting commonly known as "narrowing", and which consists in eliminating end needles from the successive courses and thereby obtaining fewer loops and decreasing the width of the fabric. For instance, to take figures from actual practice, where the section 21 is knitted with 304 needles, and the narrow portion of section 25 is to have the width obtained by 240 needles, the effect of the 35 gradual reduction in width is obtained by gradually eliminating from knitting action some of the end needles of the 304 needles, until, when the narrow portion is reached, only 240 needles remain active.

40 45 In knitting the portion 23, in which the width is to increase as the knitting progresses, the reverse process is employed, that is, needles are gradually added. For example, to take actual figures, where portion 19 requires 240 needles, and portion 21, 304 needles, the transition will be 50 made by adding needles, this addition being by uniform increments where a uniform taper is desired.

55 It will therefore be obvious that the many advantages of my improved construction may be obtained by a simple process that comprises a continuous and uninterrupted process of knitting, without the necessity of a transfer operation, and initiated by the knitting of the single 60 layered welt portion, the knitting of a tapered portion 21 by the gradual introduction of extra needles, and the continuation of the knitting by standard methods, as desired.

65 In connection with the illustrative embodiment disclosed herein I have described the widening of section 23 as obtained by the introduction of extra needles and the formation of additional loops, but it is to be understood, as has already been mentioned, that a similar effect might be 70 obtained by making the portion 23 of the same

width as the welt, but forming the loops, so that they are capable of greater expansion, and this effect may also be made progressive.

While I have herein described and illustrated one embodiment of my invention and one manner of practicing the same, it will be understood that many other embodiments thereof may be made and that it may be practiced in many other ways without exceeding the scope of my invention or departing from the spirit thereof, as defined in the appended claims.

Having described my invention I now claim:

1. In a full fashioned stocking, a single layer 15 welt portion of a circumference adapted to grip the leg of the wearer above the swell of the calf under elastic tension, said welt portion being of relatively heavy yarn, and of a loop formation and arrangement giving relatively great expansibility, whereby said welt portion will be relatively 20 resilient and yet be sufficiently resistant to provide a gripping action, and said welt portion being further of a normally uniform circumference throughout its width, and the number of loops in each course thereof being constant, said stocking having further a portion, adapted to seat on the leg at the swell of the calf, that is normally 25 of greater circumference and loops per inch than said welt portion, a portion intermediate said calf portion and said welt portion having at one end the circumference and loops per course of the 30 welt portion and at its other end the circumference and loops per course of the calf portion, and said intermediate portion gradually changing in loop number and circumference from its welt end to its other end, and the portions 35 below said calf portion decreasing in circumference, whereby said stocking will be form fitting throughout, as well as self-sustaining, and said portions of the stocking below the welt portion being of relatively light yarn.

40 2. A full fashioned stocking having a relatively resistant elastic single layer welt portion of relatively heavy yarn and of a loop formation and arrangement adapted to give the desired characteristics, and adapted when the stocking is 45 seamed to engage the leg of a wearer below the knee and above the swell of the calf with a resilient gripping action, and said welt portion having a uniform circumference corresponding to a number of loops of the order of 250, and 50 having joined thereto a portion of relatively light yarn and of a circumference gradually increasing by reason of having loops added to the successive courses, the circumference of said portion where it joins the welt portion being the 55 same as that of the welt portion and increasing until a circumference corresponding to a number of loops of the order of 300 is reached at the point where the stocking engages the swell of the calf, whereby the stocking will be self-sustaining as a result of the supporting effect due to the engagement of said described portions of the stocking with the leg portions above the swell of the calf and below the knee, and the 60 number of loops in the leg engaging portions of the stocking below the knee decreasing by eliminating loops in the successive courses thereof, and being joined to a foot portion of the usual construction.
